UNITED STATES PATENT OFFICE.

ALEXANDER CAMERON, JR., OF RICHMOND, VIRGINIA.

BOX OR CAN PROVIDED WITH MEANS FOR OPENING SAME.

SPECIFICATION forming part of Letters Patent No. 633,986, dated October 3, 1899.

Application filed January 3, 1899. Serial No. 700,987. (No model.)

To all whom it may concern:

Be it known that I, ALEXANDER CAMERON, Jr., a citizen of the United States, residing at Richmond, in the county of Henrico and State of Virginia, have invented certain new and useful Improvements in Boxes or Cans Provided with Means for Opening the Same; and I do hereby declare the following to be a full, clear, and exact description of the invention, such as will enable others skilled in the art to which it appertains to make and use the same.

My invention relates to improvements in boxes or cans provided with means for opening the same; and it consists, essentially, of a can having a permanent thin top and a removable cover, which latter is provided on its under side with a downwardly-extending fixed knife or cutter, located very close to the outer edge of the cover, and a packing interposed between the said knife or cutter and said vertical flange of said cover, whereby when the cover is placed on the can so that the said knife or cutter extends or projects over the outer edge or surface of said box or can, the said cutter being located at such a distance from the vertical flange of the cover that it can be applied over the outer edge of the can and rest, during shipment, between the outer surface of the can and the inner surface of the cover, and when said cover is removed will spring back to a vertical position, so as to be in line with the tagger top when the cover is applied to the can to cut out the said top.

It also consists of a can having a permanent thin top and a removable cover, which is provided on its under side with a downwardly-extending fixed knife or cutter and a packing interposed between the said knife or cutter and the vertical flange of the cover, whereby when the cover is placed on the can, so that the said knife or cutter extends or projects over the outer edge or surface of said box or can, the said cutter will be prevented from being bent too far outward, and thus rendered incapable of returning to a vertical position when the said cover is removed from the can for the purpose of cutting out the tagger top when desired to open the can, the flange of the outer cover being cut away on the line with the knife or cutter to assist in removing the packing-strip.

In the accompanying drawings, Figure 1 is

a perspective view of a box or can, showing the removable cover slightly raised above the same, with the packing-strip removed. Fig. 55 2 is an inverted perspective view of the removable cover with the packing-strip in position on the same. Fig. 3 is a perspective view of a can, showing the cover in the act of being applied to the same and partly broken away; 60 and Fig. 4 is a vertical longitudinal section through the cover in position on the can as it appears when being transported.

A in the drawings represents a box or can, which is constructed circular in shape and 65 may be of any suitable material, preferably tin. The box or can is provided with a permanent thin top B, sometimes termed a "tagger" top, for hermetically sealing the contents of the can.

C represents an outer removable cover, which is made slightly larger than the box or can and is provided with a knife or cutter D, which is preferably stamped out of the material constituting the cover, but may be secured thereto in any suitable manner. The knife extends vertically from the under side of the cover and is arranged very close to the vertical flange c of the said removable cover. The said flange is also preferably provided 80 with a cut-away portion c', in line with the knife or cutter, for a purpose as will be hereinafter described.

When it is desired to place the removable cover on the can for the purpose of shipment, 85 and so that the knife or cutter will not penetrate the tagger top, the same is applied to the said can by first inclining the cover slightly, as shown in Fig. 3, so that the knife or cutter will bear upon the outer surface thereof. 90 When this is done, the cover can then be completely placed on the can, as shown in Fig. 4, and it will be observed that the knife or cutter will be on the outside of the can, and all liability of the knife or cutter penetrating the 95 tagger top is overcome.

In order to prevent the knife or cutter being bent too far outwardly, so that it cannot return to a vertical position to be in line with the tagger top when it is desired to cut out 100 the same, I interpose a piece of packing E of any suitable material, but preferably of cardboard, between the cutter and the inner surface of the vertical flange. By this construc-

tion and arrangement, as stated above, the knife will be prevented from being forced too far outwardly.

In applying the cover to the can the flange portion of the cover will yield slightly to the pressure which is brought to bear on it, the cover being sufficiently large and sufficiently yielding to admit of this and yet fit tightly on the body of the can. From practical experience I have found this to work exceedingly satisfactorily.

In order to facilitate the removal of the packing E with the fingers, I preferably cut away the vertical flange of the cover, as at c', as clearly shown in the drawings, by which construction said packing can be readily grasped. It is not, however, necessary to the successful operation of the invention that the cut-away portion should be provided, but it adds to the efficiency of the invention. As soon as the outer cover C is removed and the packing taken out the knife will immediately spring back to its vertical position again, so that when the cover is again applied to the can the cutter will be in line with the tagger top and in a position to cut out the same. This is accomplished by pressing down on the cover, which will cause the knife or cutter to penetrate the tagger top, and by revolving the cover the tagger top can be entirely cut out and access had to the goods packed in the can. The cut-out tagger top can then be thrown away and the outer removable cover replaced to protect the goods until they are consumed.

The essential feature of my invention and by which I am enabled to accomplish the above results consists in locating the knife or cutter very close to the flange of the cover and in interposing a packing-strip between the cutter and the said flange. If the packing-strip were not employed, the cutter, in applying the cover, as above described, would be so far bent out that it would not automatically return to a vertical position, and if located too far from the flange of the cover it

would be impossible to apply the cover to the can in the manner above described to prevent the cutter penetrating the tagger top.

Having now described my invention, what I claim as new, and desire to secure by Letters Patent, is—

1. A box or can comprising in its construction a suitable body portion having a permanent thin top and a removable cover having a vertical flange and provided on its underside with a downwardly-extending knife or cutter, and a packing interposed between the knife and the inner surface of the flange of the cover, the cutter being located at such a distance from the flange of the cover as to enable it to be applied over the outer edge of the can and lie between the said outer edge and the inner surface of the flange of the cover during shipment and when the cover is removed, to spring back into a vertical position to be in line with the top to cut out the same, substantially as described.

2. A box or can comprising in its construction a suitable body portion having a permanent thin top and a removable cover having a vertical flange and provided on its underside with a downwardly-extending knife or cutter, the said flange being cut away in line with the cutter, and a packing interposed between the knife and the inner surface of the flange of the cover, the cutter being located at such a distance from the flange of the cover as to enable it to be applied over the outer edge of the can and rest between the said outer edge and the inner surface of the flange of the cover during shipment, and when the cover is removed, to spring back into a vertical position to be in line with the top to cut out the same, substantially as described. 85

In testimony whereof I hereunto affix my signature in presence of two witnesses.

ALEXANDER CAMERON, JR.
